UNITED STATES PATENT OFFICE.

STEFAN REVAY, OF JOHNSTOWN, PENNSYLVANIA.

RAIL TIE AND FASTENER.

1,266,991.

Specification of Letters Patent.

Patented May 21, 1918.

Application filed January 9, 1918. Serial No. 211,028.

To all whom it may concern:

Be it known that I, STEFAN REVAY, a subject of the King of Hungary, residing at Johnstown, in the county of Cambria and 5 State of Pennsylvania, have invented certain new and useful Improvements in Rail Ties and Fasteners, of which the following is a specification.

The primary object of this invention is 10 the provision of a form of railway tie and means for securing rails thereon which is simple in construction and possesses great strength as well as permitting the assembling and disassembling of the structure at 15 will whenever desired.

A further object of the device is to provide a ready means for detachably securing rails in their operative positions upon the ties of a roadbed without the necessity of 20 perforating the rails, it only being required to employ a wrench in applying or detaching the device.

In the drawing forming a part of this application and in which like designating 25 characters refer to corresponding parts throughout the several views,

Figure 1 is an elevational view of a railway rail operatively secured upon ties after the manner of my invention.

Fig. 2 is a vertical sectional view thereof taken upon line II—II of Fig. 1.

Fig. 3 is a horizontal sectional view taken upon line III—III of Fig. 1, and

Fig. 4 is a perspective view of one of the 35 locking members employed with the device.

My invention broadly consists of means for supporting railway rails such as 10 upon the roadbed 11 in track formation and comprises metal ties 12 of I-beam form with the 40 rail detachably secured thereon by means of locking members 13.

These locking members 13 are in the form of complementary plates 14 having transverse shoulders 15 at one end thereof and with a 45 hook 16 laterally projecting from one end of such shoulder, the body of each plate being provided with a square perforation 17. The rail such as 10 is mounted upon the top 18 of the tie 12, transversely thereof in the usual manner, and fish plates 19 having base flanges 20 are oppositely engaged with the rail 10 with the flanges 20 thereof seated 50 upon the base flanges 21 of the rail and with the upper edge portions 22 of the fish plates 55 seated beneath the tread 23 of the rail.

The locking members 13 being comple-

mentally formed as heretofore described, a pair of said members 13 are arranged in engagement with each other flatly contacting the web 23' of the tie 12 and with the hooks 60 16 of the locking members projecting upwardly through slots 24 in the top 18 of the tie while the angular end portions 25 of the hooks engage within sockets 26 formed in the edges of the fish plate flanges 20. 65

A bolt 27 having a squared shank is positioned through the perforations 17 of the locking members and also through a squared opening 28 in the tie web 23', and is provided with a lock nut 29 threaded upon its 70 outer end for retaining the locking members upon the tie 12. The locking members 13 are securely held in engagement with each other and mounted upon the tie 12 by the bolt 27, whereby the hook 16 firmly 75 locks the fish plates 19 in contact with the rail 10 thereby preventing any movement of the rail under traffic conditions. It will be seen that by removing the bolt 27, the locking members 13 may be readily released 80 permitting free movement of the rail 10. With my device it is unnecessary to perforate the railway rail so that when my form of tie with its locking members, bolts and fish plates is provided, the railway line 85 may be quickly constructed with the use of only a wrench, while the line may also be readily disassembled by the use of such an implement. It will be seen that the squared perforations 17 and 28 are adapted to maintain the bolt 27 against turning during the 90 operative rotation of the nut 29 thereon. This device is serviceable in connection with the laying of temporary tracks such as those employed for army use and for mine and 95 similar purposes.

What I claim as new is:—

1. A device of the class described comprising a railway tie of I-beam formation having vertical perforations through the 100 top thereof, fish plates adapted for engaging railway rails mounted upon the tie provided with marginal sockets, and complementary formed locking members secured to the web of said tie having hooks projecting through the said perforations and seated within the said sockets when the device is operatively assembled. 105

2. In combination with a railway rail, a supporting I-beam positioned transversely 110 beneath said rail and having perforations through the top of the beam adjacent the

opposite sides of the bottom of the rail, locking members having complementally formed plate portions detachably secured to the web of said beam and provided with 5 inwardly extending hooks projecting through the said perforations and retainingly overlying the base flanges of said rail.

3. In combination with a railway rail, a supporting I-beam positioned transversely beneath said rail and having perforations through the top of the beam adjacent the opposite sides of the bottom of the rail, locking members having complementally formed plate portions detachably secured to 10 the web of said beam and provided with inwardly extending hooks projecting through the said perforations and retainingly overlying the base flanges of said rail, fish plates oppositely positioned against the 15 tread portion and upon the base flanges of said rail and having marginal sockets adjacent said perforations and adapted to re-

ceive the said hooks when the device is assembled.

4. A device of the class described comprising supporting I-beams having spaced perforations through the top thereof, a railway rail transversely mounted upon the top of the beam with its opposite sides arranged inwardly of the outer portions of such perforations, angular fish plates engaging the opposite sides of the rail having marginal sockets positioned above such perforations, locking plates provided with shoulders positioned in complemental arrangement upon 30 the web of the beam, hooks carried by said shoulders projecting through said perforations and seated within the said sockets, and retaining bolts detachably secured through the said beam and plates when the device 35 is assembled.

In testimony whereof I affix my signature.

STEFAN REVAY.

Copies of this patent may be obtained for five cents each, by addressing the "Commissioner of Patents, Washington, D. C."
